(57) **CLAIM**

The ornamental design for a pram as shown and described.

DESCRIPTION

FIG. 1 is a rear perspective view of a pram showing my new design;

FIG. 2 is a rear elevation view of the pram of FIG. 1;

FIG. 3 is a front elevation view of the pram of FIG. 1;

FIG. 4 is a top plan view of the pram of FIG. 1;

FIG. 5 is a left elevation view of the pram of FIG. 1, with the right elevation view being a mirror image of the left elevation view;

FIG. 6 is a front perspective view of an alternate embodiment of a pram;

FIG. 7 is a left elevation view of the pram of FIG. 6, with the right elevation view being a mirror image of the left elevation view;

FIG. 8 is a front elevation view of the pram of FIG. 6;
FIG. 9 is a rear elevation view of the pram of FIG. 6; and,
FIG. 10 is a top plan view of the pram of FIG. 6.

The broken lines shown in the figures represent environment and form no part of the claimed design.

1 Claim, 10 Drawing Sheets
